SYSTEM OF TRANSMITTING IMAGES

John W. McKay, Brooklyn, N. Y., assignor to
 National Television Corporation, Wilmington,
 Del., a corporation of Delaware

Application February 6, 1933, Serial No. 655,350

7 Claims. (Cl. 178—6)

This invention relates to a system of transmitting images from one place to another by scanning an object field, transmitting the plurality of light and dark elements thus obtained into a continuous series of impulses, and translating said impulses into light again and arranging them in an orderly manner to form the image.

In transmitting images by television at the present time, an object field is cut up into a plurality of lines, these lines being scanned successively at the transmitting end and re-arranged again by a scanning device at the receiving end. There is no particular standard for the number of lines per picture for transmitting images. In some cases as low as forty-five lines per picture have been used with good results while in other cases, especially where more detail is desired, 120 lines may be desirable or even as high as 180 lines per picture.

It is one of the objects of the present invention to provide a television system which is usable for transmitting images at different numbers of lines per picture.

Another object of the invention is to provide a television apparatus which may be changed to transmit or receive a different number of lines per picture while the machine is in operation.

Another object of the invention is to provide a television system in which the number of lines per picture may be changed without changing the size of the picture.

Other objects and objects relating particularly to the construction and assemblage of the various parts will be apparent as the description proceeds.

Several embodiments of the invention have been illustrated in the accompanying drawings in which:

40 Fig. 1 is a sectional plan view of a television receiving apparatus;

Fig. 2 is a sectional elevational view of the apparatus taken on the line 2—2 of Fig. 1;

45 Fig. 3 is a sectional elevational view of the scanning device used in the apparatus of Fig. 1;

Fig. 4 is a fragmentary plan view of a clamping device for the elements of the scanning drum;

50 Fig. 5 is a sectional plan view of the scanning drum;

Fig. 6 is a sectional elevation of the drum shaft illustrating a portion of the mechanism for changing the plates while in motion;

55 Fig. 7 is an elevational view of the upper and

lower ends of the plate controlling sleeve, showing additional operating mechanism;

Figs. 8 and 9 are plan views of the two different plates used in the drum;

Fig. 10 is an elevational view of a modified 5 form of scanning drum;

Figs. 11 and 12 are plan views of the two different plates used in the drum of Fig. 10;

Fig. 14 is an elevational view of the shaft and plate-supporting sleeve with the plates removed;

Fig. 15 is a sectional plan view taken on the line 15—15 of Fig. 13;

Fig. 16 is a sectional elevational view of some 15 of the plates taken on the line 16—16 of Fig. 15, and showing the plates set for receiving a sixty line picture;

Fig. 17 is a sectional elevational view similar to Fig. 16 but showing the plates set for receiving 20 a 120 line picture;

Fig. 18 is a sectional elevational view of a portion of the plates taken on the line 18—18 of Fig. 15, and showing the plates set for a sixty line picture;

Fig. 19 is a sectional elevation of the same 25 plates showing them set for a 120 line picture;

Fig. 20 is a sectional side elevational view of a different type of scanning apparatus with means to change the number of lines per picture; 30

Fig. 21 is a plan view of a portion of the changing mechanism of Fig. 20 taken on the line 21—21 of Fig. 20;

Fig. 22 is a sectional elevational view of the plate controlling shaft of the apparatus shown 35 in Fig. 20;

Fig. 23 is a sectional plan view of the drum taken on the line 23—23 of Fig. 20;

Fig. 24 is a sectional plan view taken on the line 24—24 of Fig. 20 and showing only the uppermost plate below the section line; 40

Fig. 25 is a sectional plan view taken on the line 25—25 of Fig. 20;

Fig. 26 is a fragmentary elevational view of a portion of the shaft showing the keyway for securing the plates in one position; 45

Fig. 27 is a fragmentary elevational view of a portion of the shaft showing the other keyway for securing the plates in their other position;

Fig. 28 is a sectional plan view showing the 50 means of shifting or changing the distance of the light source from the drum to compensate for the change in the number of lines per picture;

Fig. 29 is a fragmentary front elevational view of the invention applied to a scanning disc and 55

showing the disc adapted to be used with a sixty line picture;

Fig. 30 is a fragmentary front view of the same scanning disc arranged to scan a picture at the 5 rate of one hundred and twenty lines per picture;

Fig. 31 is a sectional side elevational view of the television apparatus using the scanning discs of Figs. 29 and 30;

Fig. 32 is a sectional front elevational view 10 taken on the line 32—32 of Fig. 31; and

Fig. 33 is a sectional elevational view of a portion of the changeover mechanism taken on the line 33—33 of Fig. 31.

Referring now more specifically to the drawings, the invention is shown in connection with a 15 scanning apparatus as disclosed in the application of Arno Zillger, Ser. No. 626,579, filed July 30th, 1932. In this application the scanning apparatus comprises a drum formed of a plurality 20 of plates, stacked one upon the other, and each having a reflecting edge which is almost as long as the diameter of the drum. Each plate is turned slightly with respect to the plates adjacent to it so that the angles formed between adjacent reflecting edges are equal and the edges 25 themselves form a helix around the circumference of the drum with the reflecting surface of the last plate on the bottom, forming the same angle with the top plate as exists between all of 30 the other plates.

A linear source of modulated light varying in accordance with an incoming television signal is positioned at the proper distance away from the drum so that only its reflection can be observed 35 in the drum. When the drum is rotated at a speed which synchronizes with the speed of the transmitting scanning device, the reflecting surfaces will successively cause the reflection of a small portion of the light source to flash across 40 the observer's field of vision, and as these flashes of light are modulated in accordance with the incoming signal the image will appear to the observer to be slightly behind the drum and is built up by the visual memory of the observer who only 45 sees one small point of light at any given instant.

In the application above referred to, the plates 50 are all rigidly secured on a shaft, there being sixty plates, or one for each line of the picture. With such a drum only sixty lines per picture 55 can be scanned and if it is desired to transmit or receive a picture with a different number of lines per picture the scanning device in question becomes useless. The present invention provides means to shift the plates so that they will assume a different angular relation with each other and hence a picture of a different number of lines may be received or transmitted.

The construction of one apparatus for shifting these plates is best seen in Fig. 3. Here a 60 motor 1, adapted to run in synchrony with the motor of the transmitting station either by virtue of the same alternating current cycle in the power supply line of both or by some synchronizing apparatus (not shown) such as the toothed wheel well known in the art, is mounted in a suitable 65 cabinet 2, in a vertical position with the shaft 3 extending upwardly in front of a window 4 provided in the cabinet for viewing the image. A short distance from the motor 1, the shaft 3 is provided with a shoulder 5 upon which rests a 70 sleeve 6 which is rotatably mounted upon the shaft 3 and is approximately as long as the number of reflecting plates are high. The shaft has a second shoulder 7 a trifle above the top of the 75 sleeve 6 and a short portion 8 of the shaft im-

mediately above the shoulder is threaded to receive the nut 9 which may be tightened down against the shoulder and which therefore secures the sleeve 6 upon the shaft with a slight clearance to provide for rotation therebetween. 5 The remaining portion of the shaft is also threaded to receive a small internally threaded sleeve 11 provided for the purpose of securing the plates in position in a manner to be herein-after described. The extreme upper end of the 10 shaft is provided with a small wheel 12 which rests upon a shoulder 13 and is secured on the shaft by means of a pin 14. The purpose of this wheel will be described later.

The sleeve 6 has a depending skirt or extension 15 which is slightly larger in diameter than the lower portion of the shaft 3 below the shoulder 5 and extends down almost to the motor and is provided for the purpose of controlling the rotation of the sleeve. A flange 16 may extend outwardly from the upper edge of the skirt 15 and is provided to support the stack of plates upon the sleeve. To this end a heavy plate 17 is positioned over the sleeve 6, having a hole in the center thereof sufficient to fit over the skirt 25 15 so that the plate will rest upon the rim or flange 16. A plurality of plates 18 (see Figs. 8 and 9) are stacked in a helix upon this supporting plate 17, each being provided with a hole 19 in the center to receive the sleeve 6. 30

The plates 18 may be rectangular in shape as illustrated in Fig. 8 having the rectangular cut out portion 20 on each side of the center to lighten the weight thereof. In the present embodiment being described one side or edge 21 only of the 35 plate is used in building up the image and this edge is made highly reflecting, being preferably optically ground and polished so that it is perfectly straight with sharp edges or corners to fit as closely as possible against the adjacent 40 plate. The edge 21 is preferably formed parallel with the axis of the shaft 3 but this is not essential so long as all the reflecting edges of all the plates have the same angle with respect to the axis. The opposite edge 22 of each plate and the 45 ends 23 need not be provided with a reflecting surface and are bevelled or ground down at a different angle to that of the reflecting surface 21 so that as the drum rotates no light will be reflected from the edge 22 or end edges 23 in 50 the same direction as the light from the reflecting edges 21.

The plates as just described are stacked on the sleeve 6, the number of plates used and the angle between them being determined by the 55 number of lines per picture which it is desired to transmit or receive. For purposes of illustration I have arbitrarily chosen an apparatus for use with either sixty lines or one hundred and twenty lines per picture. To accomplish this 60 purpose I provide 120 plates which when arranged for sixty line transmission are stacked in pairs, each pair being turned at an angle of 6° with the pair immediately above or below it so that a complete helix is formed from top to bottom of the drum and the uppermost pair of plates have an angle of 6° with the lowermost pair. Thus arranged each pair of plates forms one line 65 of the sixty line picture with the two edges 21 lying side by side and in the same plane. One 70 plate of each pair is secured to the sleeve 6 while the other plate of each pair is secured to the shaft 3. When it is desired to change from a sixty line picture to a one hundred and twenty line picture I have only to rotate the shaft and sleeve with 75

respect to each other through an angle of 3°, and every other plate in the stack will move through 3°, and the result is that there will be one hundred and twenty plates positioned at 3° apart, forming a complete helix from top to bottom with the upper plate spaced 3° from the lower plate. When in this position the drum will scan 120 lines per picture or for each rotation of the drum.

One of each pair of plates is secured to the sleeve 6 and the other of each pair to the shaft in the following manner: The lowermost plate A of each pair is provided with a keyway 24 which is engaged by a key 25 secured to the shaft 3 and passing through a slot 26 which is provided in the sleeve 6 (see Figs. 5, 8, and 9). I preferably provide the key 25 parallel with the axis of the shaft and cut the keyways 24 in the alternate plates A at an angular distance of 6° apart so that when the plates are slipped onto the shaft they assume their proper position of 6° apart. However, if desired, the key may be made spiral or helical and the keyway 24 may be cut exactly the same for each plate. The slot 26 in the sleeve 6 is exactly wide enough to permit the shaft 3 to turn through an angle of exactly 3° with respect to the shaft.

The uppermost plate B of each pair is provided with a keyway 27 into which is adapted to fit a key 28 which is rigidly attached to the sleeve 6. The plate A is provided with a slot 29 which surrounds the key 28 and permits movement of the sleeve with respect to that plate while the plate B is provided with a cutout slot 30 which is larger than the key 25 and permits movement of the shaft without interference between the key 25 and that plate.

It will thus be seen that all of the plates A are attached to the shaft 3 and will rotate with it through a limited angle depending on the size of the slot 26 in the sleeve 6, while all of the plates B are rigidly attached to the sleeve 6 and will rotate with the sleeve. If the sleeve is then rotated in a counter clockwise direction with respect to the shaft 3 the plates will align themselves as is shown in Fig. 5 to give a sixty line picture with each pair of plates in alignment. If the sleeve is, however, rotated in a clockwise direction with respect to the shaft, all of the plates B will turn in a clockwise direction a distance of 3° so that the plates will then arrange themselves exactly 3° apart for the one hundred twenty line picture.

It is desirable to secure the plates in position when they are either in the one hundred and twenty or sixty line arrangement so that there can be no slipping while the picture is being received, and it is also necessary to release this securing means when it is desired to shift the plates. It may also be desirable to shift the plates while the machine is in motion and an arrangement for accomplishing this purpose has been illustrated.

In order to secure the plates in position I provide a yoke or spider 31 (Fig. 3) which is in the form of a rectangular plate slightly shorter than the reflecting plate and is provided at its ends with down turned portions 32 adapted to bear upon the ends of the uppermost plate. These downturned portions 32 may also be provided with a pair of pins 33 adapted to fit in the inner corners of the cutout portions 20 of the uppermost plate so that the yoke will not move or rotate out of its proper position with respect to the upper plate. The yoke 31 is provided with a suit-

able hole 33' which is adapted to fit over the nut 9 (already described) and may have vertical movement without binding on this nut. The sleeve 11 already described is provided at its lower end with a flange 34 which has an outer downwardly extending ring 35 adapted to bear upon the spider 31, so that the sleeve 11 may be rotated in one direction to cause it to thread downwardly on the threaded portion 10 of the shaft and thus press the spider downwardly against the plates and press the plates together. It will be noted that the spider engages the plates by the portion 32 at the ends of the plates so that the plates are not forced together at the center which might cause slight distortion. To loosen the plates for changing their arrangement, the sleeve 11 is rotated in the opposite direction which thereupon relieves the pressure on the spider 31.

In order to permit rotation of the sleeve 11 while the drum is rotating, I provide a spindle 36 which extends through a slot 37 in the end 10 of the shaft so that it is free to be moved up and down through a limited distance but will move in the plane of its axis when the shaft is rotated. The spindle 36 is provided at each end thereof with a roller 38 which is rotatably mounted on the end of the spindle and is adapted to move in a runway 39 which is provided in the inner side of a sleeve 40. The lower bearing ring 39a of the runway is made removable to facilitate assembly of the spindle and rollers. The sleeve 40 is movable in a cylinder 41 mounted on a bracket 42 which is secured to the cabinet 2 in any desired manner (not shown). The sleeve 40 is provided with two or more outwardly extending pins 43 which pass through helical slots 44 in the cylinder 41 so that rotation of the sleeve 40 will cause it to have limited vertical movement with respect to the cylinder. The spindle 36 also passes through a pair of slots 45 in the sleeve 40 which are so curved that movement of the spindle 36 up or down will cause rotation of the sleeve 11 with respect to the shaft. This is clearly illustrated in Fig. 6. When the sleeve 40 therefore moves up and down within the cylinder 41, the sleeve 11 is caused to be rotated back and forth with respect to the shaft while at the same time the shaft and sleeve 11 may be rapidly rotating with the rollers 38 running in their runway 39 in the sleeve 40. The rotation of the sleeve 11 as has already been explained, will loosen or tighten the plates of the drum and by raising and lowering the sleeve 40 therefore the plates may be loosened or tightened regardless of the speed of the machine.

In order to raise or lower the sleeve 40 I provide another sleeve 46 which fits on the outside of the cylinder 41 and is rotatably positioned thereby means of a nut 47 which may be screwed onto the threaded lower end of the cylinder. The sleeve 46 may be provided with a pair of vertical grooves 48, clearly shown in Fig. 7 as well as Fig. 3, so arranged that rotation of the sleeve 46 will cause the pins 43 which lie in the groove 48, to be rotated, thus causing either upward or downward movement of the sleeve 40, depending on the direction of rotation of the sleeve. Clockwise rotation of the sleeve as viewed from above, will cause the pins 43 and the sleeve 40 to which they are attached to move upwardly, while rotation in a counter clockwise direction will reverse the movement of the sleeve 40.

In order to rotate the sleeve 46 I provide at its upper end a ring of bevelled gear teeth 49 which mesh with a bevel gear 50 mounted on a shaft 51.

supported for rotation in bearing members 52 forming part of the bracket 42 and passing through a hole 53 in the cabinet wall where it terminates in a knob 54 which may be manually rotated one way or the other. From this description it is evident that rotation of the knob 54 in a clockwise direction will cause the sleeve 46 to rotate in a counter clockwise direction and the sleeve 40 to move upwardly carrying with it the spindle 36, thereby causing the sleeve 11 to loosen the plates on the drum. Rotation of the knob 54 in the other direction will cause the sleeve 11 to tighten the plates on the drum, all this taking place independently of the rotation of the drum so that it can be moving at full speed during this adjustment.

The method for rotating the sleeve 6 with respect to the shaft 3 may be worked out in a somewhat similar manner. To this end a spindle 55 20 is positioned in a slot 56 (Fig. 6) in the shaft 3 and extends through offset slots 57 in the skirt 15 which is attached to the sleeve 6. The slots in the skirt 15 are so arranged that movement of the spindle up or down causes the 3° rotation 25 between the shaft and sleeve.

In order to move the spindle up and down while the machine is in operation, I provide a pair of rollers 58 rotatably mounted on the ends of the spindle 55 and adapted to roll in a runway 30 59 provided in a sleeve 60. The upper guide 61 of the runway 59 may be removably held in place, if desired, by suitable screws 62 to permit the insertion of the spindle with its accompanying rollers. The sleeve 60 may be mounted for limited 35 vertical movement in a cylinder 63 which is attached to the motor casing and is provided with a pair of helical slots 64 through which extend a pair of pins 65 extending outwardly from the sleeve 60. The pins 65 also pass through a pair 40 of vertical slots 66 in a sleeve 67 rotatably mounted about the cylinder 63. This sleeve may be held in position upon the cylinder by means of a nut 68 threaded onto the upper end of the cylinder while the lower end of the sleeve rests 45 upon a flange 69 forming part of the cylinder. The lower end of the sleeve 67 is provided with a bevel gear 70 which meshes with a small bevel gear 71 mounted on a shaft 72 which is supported in bearing members 73 attached to an 50 arm 74 which forms an extension of the flange 69 on the cylinder 63. The shaft 72 extends through an opening 75 provided for that purpose in the wall of the cabinet 2 and terminates in a knob 76 which may be manually operated. 55 Rotation of the knob will cause rotation of the sleeve 67 and consequent vertical movement of the sleeve 60, as the pins 65 run in the curved groove 64, which in turn causes the spindle 55 to move up or down, depending on the rotation 60 of the knob, and the sleeve 6 to rotate with respect to the shaft 3.

Let us assume that a sixty line picture is being received with the drum rotating at the proper synchronous speed and it is desired to change to one hundred and twenty lines to pick up a signal which is being broadcast in that manner. The plates will be positioned as indicated in Fig. 5, and the various parts will assume the positions shown in Fig. 3. Without stopping the motor 65 then, the operator turns the upper knob 54 in a clockwise direction. This rotates the sleeve 46 in a counter clockwise direction, as viewed from above, and causes the pins 43 to move in the slot 44 so that they are raised upwardly and thereby 70 raise the sleeve 40, thus causing the spindle 36

to move upwardly, and as the spindle engages the slot 46 in the sleeve 11, the sleeve is unscrewed, thereby releasing the pressure against the spider 31 and loosening the whole stack of plates. With the plates thus loosened the operator rotates the knob 76 in a clockwise direction. This turns the sleeve 67 also in a clockwise direction and causes the pins 65 to move downwardly in the grooves 64 resulting in the lowering of the sleeve 60 which pulls downwardly with it the spindle 55. Downward movement of the spindle 55 causes the sleeve 6 to rotate in a clockwise direction causing the upper plate B of each pair of plates to move in a clockwise direction with respect to the lower plate A, and continual rotation of the knob until it can be turned no farther will cause these plates to assume their proper position with the 3° angular spacing.

When the plates have been properly positioned 20 by the adjustment of the knob 76 the knob 54 is again rotated this time in a counter clockwise direction thereby rotating the sleeve 46 in a clockwise direction and causing the pins 43 and accompanying sleeve 40 to lower, thereby lowering 25 the spindle 36 and causing the sleeve 11 to be threaded down upon the threaded portion 10 of the shaft until it presses the spider 31 against the plates thereby holding them rigidly in position.

In a scanning drum of this nature it is important that the light be positioned a proper distance away from the drum. This distance depends on the angle between the plates and the size of the drum. For a drum made up of sixty 35 surfaces spaced at 6° apart and being approximately 6" high with each reflecting surface being about 7.2" wide, (the proportion for a standard motion picture), the light is necessarily positioned about 48 inches away from the drum. 40 With this positioning of the light the image received will exactly fill the flat surface of the drum which appears when it is rotated. If the light is moved any nearer to the drum it will be reflected from more than one surface at a time 45 and hence as it is moved toward the drum another image will appear on the side of the first image, both images being narrower but having the same height. Further movement of the light towards the drum will cause additional images 50 to appear until half a dozen or more are crowded onto the drum, the horizontal dimension of each image being shortened accordingly. In like manner if the light is moved away from the drum the image becomes wider and wider until only 55 a portion of it can be seen on the drum without moving the eye from side to side. Because of this fact it is necessary to change the effect of the distance of the light from the drum when the plates are shifted from their sixty line position to their 120 line position.

The arrangement for carrying this into effect will be seen from an inspection of Figs. 1 and 2. In these figures are shown the preferred form of lamp for producing the line of light. This lamp 65 may be similar in construction to that described and claimed in my prior filed application Ser. No. 628,321, filed August 11, 1932, and comprises a relatively small diameter tube 78 having an enlarged bulb 79 at one end and another bulb 80 at 70 the other. The bulb 79 may contain the cathode of the lamp while the bulb 80 may contain the anode, and the tube and bulbs may be provided with an ionizable gas under reduced pressure and may preferably contain a metal vapor or 75

vapors, such as one or more of the vapors of mercury, caesium, sodium, or the like. When a current is run through this lamp and is modulated in accordance with an incoming television signal, an intense bluish white light fills the tube 78 and flickers in accordance with the signal.

Fig. 1 shows the general layout of a television receiving system embodying the invention, the apparatus being positioned in a cabinet 2 provided with an opening 4 in the front for viewing the picture. The cabinet, as shown, is approximately square in cross-section and the drum comprising the plates 18 mounted on the shaft 3 is positioned a little in front of the center. A baffle plate 81 is positioned so as to extend from the lefthand edge of the aperture 4 in a plane tangential to the circumference of the drum, and around the drum with a circular portion 82, and then in another plane 83 tangential to the drum, terminating on the righthand side of the opening 4. This baffle prevents any rays from the lamp reaching the drum from the wrong direction and also prevents the observer from seeing parts of the apparatus through the drum as it rotates. The baffle is preferably coated with a dull black finish to prevent light reflection therefrom. The lamp 77 is positioned on the other side of this baffle to the left of the drum, slightly to the rear thereof, and the light therefrom is arranged to be directed toward a mirror 84 at the rear of the apparatus which redirects the light to another mirror 85 positioned in the right forward corner of the cabinet. From the mirror 85 rays are directed through an opening 86 provided for that purpose in the baffle 83 directly onto the rotating drum. If the drum is rotating at the proper speed and the lamp is being modulated in accordance with an incoming signal, the sixty line picture appears a short distance behind the drum to an observer standing in front of the cabinet.

The lamp is provided with a cylindrical shield 87 having an open side 88 through which the rays of light may pass to reach the mirror 84. This shield 87 may be mounted upon a gear wheel 89 which is rotatably mounted in a bracket plate 90 secured to the casing wall, and has a large enough opening through its center to permit the enlarged bulb 80 of the lamp to pass. The upper end of the cylindrical shield is rotatably positioned in a second bracket plate 91 so that by rotating the gear 89 the cylindrical shield 87 is rotated about the lamp. The gear 89 meshes with a second gear 92 rotatably mounted in the bracket plate 90 upon a shaft 93 to the upper end of which is attached a bevel gear 94. The upper end of the shaft rotates in a bearing bracket 95 attached to the flange 69 which is secured to the motor casting. A second shaft 96 is also rotatably mounted in this same bearing bracket 95 and has bevel gears 97 and 98 at its ends, the bevel gear 97 meshing with the gear 94 and the bevel gear 98 meshing with the gear 70 on the sleeve 67.

Thus when the knob 76 is rotated in order to change the angle of the plates, the shield 87 is also rotated, thereby cutting off the light where it normally passes to the mirror 84 and permitting it to pass in approximately the opposite direction. A mirror 99 is positioned in the forward lefthand corner of the cabinet behind the shield 81 in such a position as to receive the light from the lamp 77 and redirect it to a mirror 100 positioned in the rear lefthand corner of the cabinet. This mirror is so positioned that it again redirects the light to another mirror 101 positioned just back of the drum and a little to the left thereof

which in turn directs the light to the mirror 84 from which it passes to the mirror 85 and to the drum.

Suitable baffles are provided to cut off all stray rays of light and thus I provide a baffle 102 which extends from about the center of the left-hand wall of the cabinet to the edge of the shield 87 and then rearwardly forming a baffle 103 extending to a point on the rear wall behind the mirror 84. The baffle 102 has an opening 104 to permit the light to pass from the mirror 99 to the mirror 100 while the baffle 103 has an opening 105 to permit the light to pass from the mirror 100 to the mirror 101. Another baffle 106 may be provided from the edge of the drum rearwardly parallel to the rays passing between the mirrors 84 and 85 and terminating at a point just clearing the rays passing from the mirror 101 to the mirror 84.

It will be evident from an inspection of Fig. 1 that when the shield is turned so that the open space 88 is forward of the light, the light will travel approximately twice the distance that it does when the open space is in the position shown. Hence the position shown will operate for a sixty line picture while the rotation of the shield causes the additional distance of light travel necessary for the one hundred and twenty line picture. The shadow box in which the drum is positioned is also provided with a lower baffle 107 and an upper baffle 108 so that in looking into the cabinet nothing can be seen except the drum itself and the reflection of the light therein.

In starting up a television receiving apparatus of this nature it is evident that the motor may not be in perfect synchrony with the transmitting motor when it comes up to speed. This will result perhaps in seeing the bottom portion of one image and the top portion of another image below it, or two side by side pictures may be seen with the dividing line in the center of the drum. In some television receivers means are provided to rotate the entire motor so that a position may be found where the image is perfectly centered with respect to the scanning device. Such an arrangement may be provided, if desired, in the apparatus comprising this invention, but I have found a much simpler way to effect the framing of the image. I merely provide a brake which acts against the motor so as to slow it down slightly whereupon it will lose several rotations and when again it picks up speed it will be in the proper synchrony. To this end the wheel 12 on the top of the motor shaft is provided with a fibre or leather coating 109. A friction element 110 is mounted on the end of a rod 111 which is slidably supported in suitable bearings 112 attached to the bracket 42. The other end of the rod is provided with a push button 113 which extends through an opening 114 in the front wall of the cabinet. With the friction element 110 spaced slightly from the rim of the wheel 12, a ring 115 attached to the rod 111 bears against the inner side of the bearing 112 and the rod is held in this position by a spring 116 which bears against the ring 115 and against one end of the inner bearing 112. The spring holds the rod in its outermost position, and when it is pushed inwardly by the finger acting against the push rod 113, the friction element pushes against the rim 109 of the wheel 12 and causes friction against the wheel in accordance with the amount of pressure exerted by the finger. The friction against the wheel 12 causes a retardation of the motor shaft 75

which can thus be caused to lose several rotations so that the phase will be changed when the motor again comes up to speed. By several pushes on the push button 113 it is possible to quickly synchronize the motor and frame the picture properly.

The foregoing description has been related to a scanning device having rectangular plates, but it is possible to use the invention in connection with plates having a different number of sides in which all the sides are used for reflecting the light for the image. In the application of Arno Zillger, Ser. No. 633,388, filed Sept 16, 1932, a scanning device is shown and described in which triangular plates are used, each edge of which is made reflecting. Triangular plates are shown because the triangular plates permit the longest reflecting surface for a given drum diameter but other plates may be used with four or more sides as desired.

Where the triangular plates are used and all of the edges are reflecting, it is necessary to only use one-third of the number of plates which would be necessary if only one edge were made reflecting. Thus for sixty line pictures only twenty plates are necessary. Each of these plates is provided with one reflecting surface which is parallel with the axis of the drum while another surface is inclined toward the lower end of the drum, and the third surface is inclined toward the upper end of the drum. The inclined surfaces all bear the same angle with respect to the axis of the drum.

Light reflected from the edges which are parallel to the axis of the drum is directed outwardly in line with the reflecting edges. Light directed from the edges which are inclined toward the bottom of the drum is directed downwardly, while the light directed from the other edges is directed upwardly. For one-third of the rotation of the drum the upwardly inclined edges direct the light upwardly where a suitable prism or other optical system makes it visible to the observer in a position above the drum. A second third of the rotation of the drum causes the straight surfaces to reflect the light into the eye of the observer who sees the image created by this portion of the drum in its proper position upon the drum. During the last third of the drum rotation the downwardly inclined edges reflect the light downwardly below the drum where it is intercepted by an optical system and redirected to the eye of the observer. This builds up the image in three parts, one above, one even with, and one below the drum, while the three series of reflecting surfaces pass the light source following the same horizontal path.

In carrying out this principle, the drum 117 of Fig. 10 comprises a plurality of triangular plates 118 mounted upon a shaft 119 for rotation by a motor 120. For a sixty line picture I provide forty plates arranged in pairs so that in effect they act similarly to the twenty plates described in the above entitled application. Each of the plates is provided with a straight reflecting surface 121, and upwardly inclined reflecting surface 122, and a downwardly inclined reflecting surface 123. Each of the reflecting surfaces has the same distance from it to the center of the plate and hence when the plates are arranged in pairs the edges 121 of the two plates forming the pair lie in the same plane as is indicated in Figs. 16 and 18. The two upwardly and the two downwardly inclined surfaces 122 and 123 respectively, 75 do not lie in the same plane, however, but take

the position indicated in Figs. 16 and 17, which gives very nearly the same effect, so that the two surfaces 122 and the two surfaces 123 act as a single surface each. When it is desired to shift from sixty lines to one hundred and twenty lines, the lower plate of each pair is rotated 3° in a counter clockwise direction similarly to the plates described in connection with the first figure, and the forty plates are then arranged at 3° intervals, each series forming one third of a 10 helix around the drum. The edges 122 and 123 will then assume a regular stepped appearance as is indicated in Figs. 17 and 19.

In order to provide for the movement of alternate plates I provide a spool 124 which is mounted on the shaft 119 and rests upon a shoulder 125 formed in the shaft. The spool is keyed to the shaft by means of the key 126. The spool comprises a central tubular member 127 which fits closely upon the shaft, and an outer cylindrical member 128 which is spaced from the inner member by the webs 129.

Inasmuch as a slight error in the position of a keyway adjacent the center of one of the plates will throw the reflecting edges of the plates out considerably, I use the spool construction in order to place the keyways as near the reflecting surfaces of the plates as possible. The spool 124, therefore, corresponds to the shaft of the construction shown in the first few figures and is provided with a key 130 which extends outwardly a short distance therefrom and is parallel with respect to the axis. A sleeve 131 is positioned around the cylindrical outer surface 128 of the spool and is provided with a slot 132 through which the key 130 extends and which permits an angular displacement of 3° between the spool and the sleeve 131. The sleeve 131 has a key 133 extending outwardly therefrom and spaced 120° in a counter clockwise direction from the slot 132.

Each of the upper plates C of each pair of the plates is provided with a keyway 134 to fit snugly against the key 133, while a slot 135 is provided spaced at 120° from the keyway 134 to receive the key 130, leaving space enough to permit angular movement of that key with respect to the plate of at least 3°. In like manner the lower plates D are each provided with a keyway 136 to fit snugly over the key 130 attached to the cylinder 128, and are also provided with a slot 137 spaced at 120° in a counter clockwise direction from the keyway 136 and large enough so that it will include the key 133 and permit movement of that key with respect to these plates.

Inasmuch as the keys 130 and 133 are parallel with the axis of the shaft the keyways in each successive pair of plates must be cut at an angle of 6° with respect to the plates immediately above or below them. The keyways in each plate of the stack therefore, will have a slightly different position with respect to the keyways in any of the other plates.

Due to the fact that the slots 135 and 137 are wider than the keys which enter them, there will be spaces in alternate plates all the way down the stack adjacent each of the keys where there is no metal, and hence these two sides of the plates or of the whole assembled stack of 70 plates will be less in weight than the other side. Hence I prefer to provide a slot 138 in the plates C and a slot 139 in the plates D which is large enough to compensate for this difference in weight and thereby balance the assembled plates. 75

Also, inasmuch as the slot 132 extends completely down one side of the outer sleeve 131, this side will be less in weight than the opposite side, and I, therefore, prefer to compensate for this difference by making the wall 140 of the cylinder 128 opposite the key 130 slightly thinner than the remainder of the cylinder so that there will be less weight on this side.

From the above description it is evident that by 5 rotating the sleeve 131 with respect to the cylinder 128, one set of plates C will be moved with respect to their next adjacent plates D so that all of the plates may be lined up at 3° spacing instead of the 6° for the pair, and the plates may be 10 thereby arranged for a one hundred and twenty line picture instead of a sixty line picture. In order to accomplish this movement of the sleeve with respect to the cylinder, I provide a flange 141 on the lower end of the cylinder upon which 15 the lower edge of the sleeve 131 rests, and on this flange I provide a pair of spaced apart lugs 142 and 143. These lugs extend upwardly a short distance beyond the bottom edge of the sleeve 131 but are spaced from the sleeve so as not to interfere 20 with its rotational movement. An adjusting spindle 144 may have one end smooth and mounted for rotational bearing in a suitable hole 145 provided in the lug 142, while the other end 25 147 of the spindle may be threaded and may have 30 threaded engagement with a tapped hole 149 in the lug 143. At the center of the spindle 144 I provide a grooved enlargement 150 to receive a slotted finger 151 extending downwardly from the sleeve 131. Rotation of the spindle 144, (which 35 may be provided in the end 147 with a slot 152 for turning it), will cause the finger 151 to move to the right or left as desired, thus rotating the sleeve 131.

The sleeve 131 may be provided with a lower 40 flange 153 upon which the plates rest, and a washer 154 may rest upon the topmost plate and be urged downwardly by a plate 155 held by a nut 156 threaded on the end of the shaft 119. The plate 155 and washer 154 hold these plates in 45 position and it is necessary to loosen the nut 156 before the plates may be shifted and the number of lines per picture changed. In making this adjustment, therefore, the operator will loosen the nut 156 and then turn the spindle 144 with a screw 50 driver until he gets the proper adjustment. When the plates have been properly positioned the nut 156 is screwed down again until the plates are rigidly secured.

In order to get the proper angular movement of 55 the plates with respect to each other, I provide a pair of pins 157 and 158 which are threaded respectively into the upper ends of the lugs 142 and 143 and may be held by lock nuts 159 and 160 respectively. When these pins 157 and 158 are 60 properly adjusted, the movement between the outer sleeve 131 and the cylinder 128 is limited to 3°, and when the sleeve is in one extreme position with respect to the cylinder, the plates are set for a one hundred and twenty line picture, while 65 when the sleeve is in the opposite extreme position the plates are set for a sixty line picture.

In Fig. 10 the general layout is indicated diagrammatically for producing a picture with this construction, although no attempt has been made 70 to show the accurate spacing of the various parts. A lamp 161, similar to that already described, is spaced from the drum 117 while an optical system, comprising the prisms 162 and 163 and a central plain glass portion 164 is positioned in the general 75 plane of the drum and light but at a different

horizontal angle therewith so that the optical system is not in the direct line between the light and the drum. As already described, rays from the lamp 161 strike the upwardly inclined reflecting surfaces 122 so as to direct rays to the prism 162 where they are bent toward the eye and give that portion of the picture the appearance of being above the drum. Rays from the straight side 121 of the plates are sent back through the plain glass 164 and appear to be about the same height as 10 the drum, while rays from the downwardly inclined surfaces 123 are reflected towards the prism 163 where they are bent toward the eye of the observer and give the appearance, for this portion of the picture, of being below the drum. 15 The general result is a complete picture which has the same width as the drum but is taller than the drum is high. All surfaces of the reflecting plates are used and a smaller number of plates are necessary than with the apparatus first described, 20 and hence the whole arrangement is lightened and cheaper.

While the scanning apparatus of Figs. 10 to 19 has been described as having a changeover device which cannot be operated when the machine 25 is in motion, it is obvious that the same arrangement as is used in the first modification shown in Figs. 1 to 9 inclusive might be used. It is also obvious that some suitable arrangement similar to that used with the first apparatus for changing 30 the distance of the light is necessary.

While the forms of the apparatus shown in Figs. 1 to 19 have been described in connection with a changeover from sixty lines to one hundred and twenty lines, it is evident that they need 35 not be limited to these two specific types of pictures, but in the simplest form of construction it appears to be desirable to change from one picture, having a certain number of lines per picture, to a second picture having a number of lines 40 which is a multiple of the number of lines of the first picture. A modification of the invention wherein it is possible to change from any number of lines to any other predetermined number of lines per picture, as for instance, from forty-five lines to sixty lines per picture, is illustrated in Figs. 20 to 28. In these figures a drum 165 is used which has a plurality of plates similar to those shown in Figs. 1 to 9, being rectangular 45 in shape and having one edge reflecting while the other edges are bevelled so as to redirect light in a different direction from the reflecting edge. 50

In this arrangement the shaft 167 of the motor 168 is hollow so that an inner shaft 169 may be moved axially therewithin. The sleeve 167 has 55 a flange plate 170 attached to it adjacent the motor upon which the plates 166 rest. The upper end 171 of the sleeve 167 is threaded to receive a nut 172, which is in the form of a sleeve, and may be screwed down upon a spider 173 which presses 60 the plates against the lower plate 170 when the nut is screwed down into position. The upper end of the sleeve 167 extends somewhat above the drum and is provided with a cap 174 which is 65 screwed down tightly over the end of the sleeve and has a hole 175 through which the inner shaft 169 may extend. The cap 174 rotates in a bearing 176 provided in one arm 177 of a frame 178, the lower arm 179 of which is attached to the motor 168. 70

The inner shaft 169 is provided with two keyways 180 and 181 which are positioned on opposite sides of the shaft. Both keyways are vertical for a distance on the shaft corresponding to the height of the stack of plates and then take 75

the form of a helix curving to the right as they approach the upper end of the shaft. The keyway 180 has its vertical section arranged to receive snugly the inwardly extending keys 182 with which each plate is provided. The upper helical section 183 of the keyway 180 is made considerably wider so that when the shaft is forced downwardly and the keys therefor move upwardly into the helical portion 183, they are free to move with respect to each other without interfering with the sides of the keyway. Each of the plates is also provided with another inwardly extending key 184 opposite the key 182 to fit into the keyway 181 on the opposite side of the shaft. The vertical section of the keyway 181 is wide enough so that it clears the edges of the keys which are bevelled as indicated in Fig. 27, to snugly fit into the helical section 185 of the keyway. When the shaft is in its uppermost position as indicated in Fig. 20, the plates are held securely by the keys 182 which lie snugly in the keyway 180. When the shaft is moved downwardly, the keys 182 slip into the enlarged helical section 183 of the keyway 180. Also, when the shaft is in its uppermost position as indicated in Fig. 20, the keys 184 are loosely positioned in the vertical section of the keyway 181 and when the shaft is moved downwardly these keys fit into the helical section 185 of that keyway where they are snugly held and accurately positioned.

If the plates are positioned for a sixty line picture with an angle of 6° between every two plates with the shaft in its uppermost position, it will be evident that as the shaft moves downwardly the angle between the plates is slightly increased, and the pitch of the helices of the keyways is so determined that the angle increases from 6° to 8° which is the angle necessary for a picture having forty-five lines. However, if the picture is to have forty-five lines which is fifteen less than the number of lines used for a sixty line picture, only forty-five of the plates beginning from the top will have to be shifted in order to get the forty-five line picture, and the remaining fifteen plates at the bottom may be left with the 6° spacing and will not be used when the picture is being received.

The sleeve 167 is provided with a pair of vertical slots 186 through which the keys 182 and 184 in the plates may pass to enter the keyways in the shaft, and these slots are widened into openings 187 where the keys on the shifting plates necessarily move horizontally to change the angles of the plates.

A mechanism is provided for loosening the nut 172 and shifting the angle of the plates while the apparatus is in motion, and this arrangement is worked out similarly to that described in the preceding pages in connection with Figs. 1 to 10. The sleeve 167 is provided with a pair of helical slots 188 on opposite sides thereof at a point just above the stack of plates where it passes through the sleeve 172, which is provided with a pair of vertical slots 189.

A sleeve 190 is mounted for vertical and rotational movement in a cylinder 191 which is attached at its upper end by means of a flange 192 to the frame 177. The sleeve 190 has a lower in-turned flange 193 which supports a ball race 194 for rotatably mounting a ring 195 within the sleeve 190. The upper side of the ball race is secured by an annular member 196 held by an externally threaded ring 197. The ring 195 is provided with a pair of oppositely and inwardly di-

rected pins 198 which extend through the slots 189 and 188 in the sleeves 172 and 167 respectively, as is indicated, so that when the pins are moved vertically with respect to the sleeve 167 they will cause a rotation of the nut 172 with respect to the sleeve 190 thereby screwing it down against the spider 173 or releasing it to loosen the plates.

On the outer surface of the cylinder 191, I provide another sleeve 199 which is rotatably held between the flange 192 and the end of the sleeve 10 by a ring 200 which is threaded onto the end of the cylinder. The sleeve 199 is provided with oppositely positioned vertical slots 201 while the cylinder 191 has a pair of helical slots 202. A pair of pins 203 are mounted to extend outwardly from the sleeve 190. These pins engage the slots 202 and 201 in the cylinder and in the sleeve 199 respectively. Rotation of the sleeve 199 causes the pins 203 to move in the slot 202 in the cylinder 191 so that the sleeve 190 is moved upwardly or downwardly depending on the rotation of the sleeve 199.

In order to rotate the sleeve 199, I provide a gear 204 at the upper end thereof which meshes with a bevel gear 205 mounted on the shaft 206. The shaft 206 is supported in a pair of bearings 207 and 208 which are formed as a part of the arm 177 of the frame 178, and the shaft extends through a hole 209 through the front of the cabinet 210 and terminates in a knob 211 which may be manually rotated. Rotation of the knob 211 in one direction will cause the nut 172 to loosen while rotation in the other direction will cause the nut to tighten irrespective of the speed of the drum.

In order to raise and lower the shaft, I provide at its upper end a disc 212 which may rotate in a ball race 213 supported in a sleeve 214 by means of a bottom flange 215 and a ring 216, threaded into the interior of the sleeve. Vertical movement of the sleeve 214 will cause the shaft to move in the same direction. A cylinder 217 is secured by means of a lower flange 218 to the arm 177 of the frame and extends upwardly terminating above the top of the shaft. This sleeve is provided with a pair of vertical slots 219 and has a sufficient diameter to permit the sleeve 214 to have both vertical and rotational movement therewithin. A pair of pins 220 extend outwardly from the sleeve 214 and pass through the slots 219 in the cylinder 217 and into a pair of helical grooves 221 formed in an outer sleeve 222 mounted for rotation on the outside of the cylinder 217. The sleeve 222 rests upon the flange 218 of the cylinder 217 and is held in position on the cylinder against vertical movement by a ring nut 223 which is threaded onto the top of the cylinder. Rotation of the sleeve 222 causes the pins 220 to move vertically in the slots 219 of the cylinder 217 and thereby causes the shaft to move up and down.

The sleeve 222 is rotated by means of a helical gear 224 which is attached to the lower end thereof and a small bevel gear 225 which meshes with the gear 224 and is mounted upon a shaft 226. The shaft 226 is mounted in a pair of bearings 227 and 228 which form a part of the arm 177 of the frame 178 and extends through an opening 229 in the front wall of the cabinet 210 where it terminates in a knob 230 for manual rotation. Rotation of the knob 230, as is evident, will cause a rotation of the sleeve 222 and a vertical movement of the inner sleeve 214 and consequently vertical movement of the shaft.

Assuming that a sixty line picture is being ob- 75

tained by this apparatus and it is desired to change to a forty-five line picture, the operator will turn the knob 211 thereby loosening the plate and then turn the knob 230 which forces the inner shaft downwardly and changes the angle of all the plates except the lower one, whereupon he will tighten the knob 211 again and the forty-five line picture may be observed.

As in the devices previously described, it is necessary to change the distance of the light source from the drum and in this modification of the invention this is accomplished in a manner somewhat similar to that described for the preceding figures. Fig. 28 shows a sectional plan view of the general arrangement wherein the cabinet 210 is provided with an opening 231 in the front thereof, and a shadow box 232 extends rearwardly from the opening around the drum 165, being cut out at 233 on the right side to permit the light from the mirror 234 to pass to the drum. A pair of vertically spaced arms 235, integral with the frame 178, extend rearwardly to the rear wall 236 of the cabinet. The lamp 237 has its upper bulb 238 above the upper arm 235 and its lower bulb 239 below the lower arm, with the slender tubular part 240 of the lamp positioned in slots 241 provided for that purpose in the arms. Suitable plates 241a may fit into the slots 241 to reinforce the arms 235. A shield 242 is positioned around the tubular portion 240 of the lamp and has a fin 243 extending outwardly from one edge and having sufficient height to fill the space between the two arms 235. The shield is positioned so as to rotate in the slots 241 in the arms 235 and its upper end is provided with an arm 244 which extends outwardly and upwardly over the edge of the frame 178 and then forwardly terminating at a point 249 adjacent the edge of the bevel gear 224 which controls the up and down movement of the inner shaft. The bevel gear 224 is provided with a lug 250 which extends outwardly therefrom and is adapted to strike the end 249 of the arm 244 to move it in one direction when the sleeve 222 is being rotated around the cylinder 217 and to strike the arm on the other side when the sleeve is rotated in the opposite direction. This permits a movement of only a few degrees of the shield 242 while the shaft operating sleeve 222 makes a complete rotation. By this means the arm 244 is caused to move through a small angle when the angle of the plates on the drum is changed.

The space 251 between the plate 243 and the other edge of the shield 242 forms a slot through which the light from the lamp throughout its length may pass, and when the plates are arranged for a sixty line picture the shield is positioned as is indicated in Fig. 28 in which case the light passing through the slot 251 may be directed toward a mirror 252 from which the light passes from the mirror 234 and to the drum in a manner already described. When the number of lines is reduced to forty-five, the shield 242 will rotate slightly in a counter clockwise direction bringing the righthand edge of the slot 251 in such a position that the rays of light are cut off from the mirror 252. However, a closer mirror 253 will receive the rays from the lamp and redirect them to the mirror 234 thus cutting down the distance of the light from the drum, as is necessary with a reduction in the number of lines. The plate 243 prevents any light from striking the mirror 253 when the shield is in position for a sixty line picture.

In Figs. 29 to 33 inclusive, I have shown an ar-

angement whereby a scanning disc may be used with the invention as I do not wish to be limited to any particular type of scanning apparatus. In this arrangement I provide a scanning disc 254 rigidly attached to a flange 255, by means of screws 256, the flange forming a part of a sleeve 257 keyed to a motor shaft 258 which is rotated by the motor 259. In this arrangement a glow lamp 260 is positioned behind the disc 254 and a lens 261 is positioned in front of it so as to enlarge the image built up by the disc as the size of such image is necessarily limited by the circumference of the disc. The lens 261 is mounted in the front of a cabinet 262. The disc 254 comprises an opaque disc of metal or other opaque material and is provided with a plurality of holes 263 (Figs. 29 and 30) arranged in a spiral around the circumference of the disc in a manner well known in the art, so that the outermost hole is spaced from the innermost hole a distance corresponding to the height of the picture to be received, while the distance between every two holes is equal to the width of the picture.

Such a disc rotating at the proper speed in front of the light 260 will completely scan an area on the illuminated electrode of the lamp equal to the size of the picture to be received, and as the light is modulating in accordance with the incoming television signal the picture appears on the edge of the disc. For a sixty line picture there are necessarily sixty of the holes 263. If it is desired, however, to make the apparatus changeable over to a one hundred and twenty line picture, I provide a plurality of holes 264 positioned midway between the holes 263 but having a diameter half the size of the diameter of the holes 263. If the holes 264 were the same size as the holes 263 and the one hundred twenty holes were permitted to scan the object field or the light source, the lines of light formed would overlap due to the fact that the diameter of the holes 263 are just sufficient to permit each hole to trace one line across the picture without overlapping. While the holes are shown somewhat exaggerated in the figure, it is well known in the art that this must be the relation between the diameters thereof and the spacing of the holes.

In front of the disc 254 and adapted to rotate with it I position a second disc 265 having a serrated spiral edge. The serrated edge of the disc 265 is formed of a plurality of fingers 266 positioned in such a way that they will normally extend outwardly between the holes 263 so as not to interfere in any way with those holes but to cover the holes 264 as is clearly illustrated in Fig. 29. Each of the fingers 266 is, however, provided with a small hole 267 which is normally covered by the disc 254 and hence serves no purpose when the disc 265 is positioned as it is in Fig. 29 for the sixty line picture. However, when it is desired to shift to the one hundred and twenty line picture, the disc 265 is rotated slightly counter clockwise with respect to the disc 254 with the result that the fingers 266 each cover one of the holes 263 thereby exposing the holes 264 as is clearly indicated in Fig. 30. That portion of each of the fingers 266 which contains the hole 267 will then fall directly over one of the holes 263, thereby cutting down the size of the hole 263 to that of the holes 264, the holes 267 in the fingers 266 being exactly the same size as the holes 264.

It will thus be seen that when the discs are in the position shown in Fig. 29, sixty holes will

be arranged in the disc for scanning, but when the second disc 265 is moved to the position indicated in Fig. 30, there will be one hundred and twenty holes equally spaced and of the same diameter. It will, however, be evident that the height of the picture which is determined by the radial distance between the outermost and innermost hole will remain the same for both the sixty line and one hundred and twenty line picture, while the width of the one hundred and twenty line picture will be half that of the sixty line picture. This alteration in the proportion of the received image is compensated for by a cylindrical lens (to be later described), which is automatically moved between the disc and the observer and tends to widen the picture to its proper dimension.

In Fig. 31 is shown the mechanism for moving the disc 265 with respect to the disc 264. To this end a sleeve 268 is rotatably mounted upon the sleeve 257 and is provided with a flange 269 to which the disc 265 is attached. The sleeve 268 may be held against axial movement on the sleeve 257 by means of a washer 270 which in turn is held by a nut 271 threaded on the reduced end 272 of the sleeve. The sleeve 268 is provided with a pair of grooves 273 which are curved so that one end is offset from the other as shown in Fig. 33. The sleeve 257 is also provided with a pair of grooves 274 which are parallel to the axis of the sleeve and align with one end of the grooves 273 when the discs are in their sixty line picture position and with the other end of the grooves 273 when the discs are in their one hundred and twenty line picture position. A pair of pins 275 extend through the grooves on each side of the shaft and are mounted in a ring 276 which rotates in a ball race 277, mounted in a sleeve 278 against a flange 279 on one side and secured by a ring 280 on the other, threaded into the end 40 of the sleeve.

The ring 276 with its pins is free to rotate with the scanning element, but upon axial movement thereof, the pins slide in the grooves 273 and 274 and cause the slight rotation of the disc 265 with respect to the disc 264 necessary to change from a sixty line picture to a one hundred and twenty line picture.

Axial movement of the ring 276 and associated parts is accomplished by moving the sleeve 278 axially. This is done by mounting the sleeve 278 for axial movement in a tubular member 281 to which it is keyed by the key 282 to prevent rotation therein. The sleeve is provided with an end closure 283 in which is a tapped hole 284 adapted to receive the threaded end of a shaft 285, the other end of which is mounted for rotation in a bearing 286 in the end 287 of the tubular member 281. This end is secured against the front wall of the cabinet and the shaft extends through an opening 288 and is provided with a knob 289 on the outside for manual manipulation. A pair of collars 290 and 291 are provided attached to the shaft on the outside and inside of the end wall 287 of the tubular member 281 so as to prevent axial movement of the shaft 285.

Rotation of the knob will cause the shaft to be threaded into or out of the end plate 283 of the sleeve 278 and thereby cause the sleeve to move backward and forward depending on which way the knob is rotated. This will move the ring 276 and associated pins axially which will cause the relative movement between the discs 264 and 265 as already described. The shifting

of the discs may thus be accomplished independently of the rotation thereof.

In order to compensate for the difference in width of the picture for a one hundred and twenty line picture as compared to a sixty line picture, I provide a cylindrical lens 292 which is mounted in a movable arm 293 attached to a sleeve 294. The sleeve 294 fits around the tubular member 281 and is held against a rib 295 formed on the tubular member by a ring nut 296 which is screwed onto the threaded end of the member. Thus mounted the arm 293 can oscillate about the tubular member, throwing the lens 292 into and out of position in front of the viewing lens 261. To oscillate the arm 293, I provide a small pinion 297 on the shaft 285 which meshes with an idler gear 298 rotatably mounted on a lug 299 attached to the inside of the tubular member 281 by means of a pin 300. The gear 298 has its upper edge extending through an opening 301 provided for that purpose in the upper edge of the tubular member 281, and meshes with rack teeth 302 provided on the inner end of the sleeve 294. The operator, therefore, has only to turn the knob 289 in order to shift both the lens and the discs to change from a sixty line picture to a one hundred and twenty line picture, and this change may be made regardless of the speed of the apparatus.

While the lens 292 has been shown as a cylindrical lens adapted to alter the image vertically and thus cut down its height, it is evident that a concave cylindrical lens might be used to increase the width of the image so as to make it the same size for either picture.

From all the above description, it is evident that I have provided a scanning apparatus for television in which the number of lines per picture may be altered and such alteration may be made while the machine is in motion so that it is possible to change from one system to another providing the apparatus is designed for those particular systems. While in all of the modifications two systems only are usable, it is evident that the apparatus may be designed to accommodate more than two systems by suitable changes in construction of the apparatus.

Where the number of pictures per second sent out by the transmitting station is the same for systems of different numbers of lines per picture the speed of the motor will be the same. However, it is obvious that if one system has a different number of pictures per second the speed of the scanning element will have to be altered. This may be done by using a motor having different synchronous speeds or by arranging suitable change speed gearing so that the speed of the scanning element may be set for the desired number of pictures per second.

All of the figures have been described in connection with receiving television apparatus but it is obvious to those skilled in the art that the same devices are adaptable to transmitting television apparatus by the substitution of a light sensitive cell for the modulated light used or the substitution of a bright constant source of light for the modulated light while a bank of light sensitive cells is positioned around the subject whose picture is being transmitted. It is, therefore, thought unnecessary to show a transmitting apparatus as the parts are essentially the same, and the invention is intended to cover both transmitting and receiving devices.

Many modifications may be made in the various structures shown and described without depart-

ing from the spirit of the invention, and I do not, therefore, desire to limit myself to what has been shown and described except as such limitations occur in the appended claims.

5. What I desire to secure by Letters Patent and claim is:

1. A television apparatus comprising a scanning device, a plurality of long thin reflecting elements on said scanning device arranged in planes substantially parallel to the axis of said device and so positioned as to scan an image with a predetermined number of lines, means to alter the position of said elements so as to change the number of lines which the device will scan on the image, a light source spaced from said scanning device a predetermined distance depending on the number of lines scanned, and means to simultaneously alter the effective position of said light source when said element altering means is operated so as to compensate for the alteration of the position of said elements and produce an image of substantially the same size for either number of lines scanned.

2. A television apparatus comprising a motor, a shaft adapted to be driven by said motor, a sleeve surrounding said shaft, a plurality of plates mounted on said sleeve in a stack, the plane of said plates being perpendicular to the axis of said shaft, each of said plates having a reflecting edge and said reflecting edges being arranged in a spiral or helix around the shaft so as to cause a complete scanning of an image with a predetermined number of lines for rotation of the shaft, means to key alternate plates to said shaft, means to key the remaining plates to said sleeve, means to rotate said sleeve slightly with respect to said drum so as to cause a slight rotation of alternate plates with respect to those adjacent to them whereby the number of lines per rotation of the shaft is altered, and means to compensate for the alteration of said reflecting surfaces so as not to substantially change the size of the image produced.

3. A television apparatus comprising a shaft, a sleeve surrounding said shaft, a motor associated with said sleeve and shaft to drive them, a plurality of flat plates mounted on said sleeve in stacked relation with the plane of the plates perpendicular to the axis of the shaft, a reflecting edge on each of said plates, said reflecting edges being positioned in a helix around said shaft so that as the shaft rotates the reflecting surfaces will scan an image with a predetermined number of lines per rotation of said shaft, means to key said plates to said shaft, and means to change the position of said shaft with respect to said sleeve whereby each of said plates is rotated through a slight angle with respect to the plates adjacent to it.

60. 4. A television apparatus comprising a sleeve, a shaft within said sleeve, means to permit axial movement of said shaft within said sleeve through a limited distance but to prevent rotational movement therebetween, means to rotate said sleeve and shaft, a plurality of plates mounted on said sleeve in stacked relation with the

plane of said plates perpendicular to the axis of said shaft and sleeve, a reflecting surface on each of said plates, such surfaces being arranged in a helix around said sleeve so as to scan an image with a predetermined number of lines when said sleeve is rotated, a keyway on said shaft having a straight portion and a curved portion, the straight portion of said keyway having a length equal to the height of said stack of plates, a key on each plate adapted to fit in said keyway, and means to shift said shaft within said sleeve so as to force said keys into the curved part of said keyway to thus change the angular relation between them. 5

5. A television apparatus comprising a plurality of stacked plates, each plate having a reflecting edge and said reflecting edges being arranged so as to form a helix around said stack of plates, a shaft passing through said stack of plates, a keyway in said shaft having a straight portion substantially equal to the height of said stack of plates and a curved portion, a key in each plate adapted to fit into said keyway to hold all of said plates in rigid position upon said shaft, means operable regardless of the rotation 20 of said shaft to shift said shaft longitudinally so as to force said keys into the curved portion of said keyway and change the angular relation of a portion of said plates. 25

6. A television apparatus comprising a stack 30 of plates, a reflecting edge on each of said plates, said reflecting edges being arranged to form a helix around said stack of plates, a shaft extending down through said plates, a keyway on said shaft having a straight portion and a curved portion, 35 a key on each of said plates adapted to engage said keyway so as to hold said plates in fixed position, means operable regardless of the rotation of said shaft to move said shaft longitudinally so as to force a portion of said keys into 40 the curved portion of said keyway and thereby cause a portion of said plates to change their angular relation with each other, and means to compensate for the angular change between the plates so as to maintain the size of the build-up 45 image. 50

7. A television apparatus comprising a plurality of stacked plates, a reflecting edge on each of said plates, said reflecting edges being arranged in the form of a helix around said stack 50 of plates, a shaft extending through said stack of plates, a keyway on said shaft having a straight portion and a curved portion, a key on each of said plates adapted to fit into said keyway so as to maintain said plates in fixed position upon 55 said shaft, means to move said shaft longitudinally within said plates so as to force said keys into the curved portion of said keyway and thereby changing the angle of a portion of said plates with respect to each other, a modulated light 60 spaced from said plates, and optical means to change the distance of said light from said plates when the angle of said plates is changed by shifting said shaft. 65
